US00D438179S

(12) **United States Design Patent** (10) Patent No.: **US D438,179 S**
(45) Date of Patent: **** Feb. 27, 2001**

(54) **WIRELESS AUDIO/VIDEO TRANSMITTER AND RECEIVER**

(76) Inventor: **Chi Wang-Tsai**, No. 262, Sec. 1,
Nan-Kuo Rd., Chang-Hua City (TW)

(**) Term: **14 Years**

(21) Appl. No.: **29/105,495**

(22) Filed: **May 25, 1999**

(51) LOC (7) Cl. **14-02**

(52) U.S. Cl. **D14/124**

(57) **CLAIM**

The ornamental design for wireless audio/video transmitter and receiver, as shown and described.

DESCRIPTION

FIG. 1 is a perspective view of wireless audio/video transmitter and receiver showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view when in use.
